UNITED STATES PATENT OFFICE.

EDWARD F. McCOOL, DECEASED, LATE OF CLEVELAND, OHIO; BY ETHEL R. McCOOL,
EXECUTRIX, OF CLEVELAND, OHIO.

GRINDING MILL.

Application filed June 19, 1922. Serial No. 569,414.

To all whom it may concern:

Be it known that I, ETHEL R. McCool, a citizen of the United States, and a resident of Cleveland, county of Cuyahoga, and State of Ohio, executrix of the estate of EDWARD F. McCool, deceased, late a citizen of the United States, and a resident of Cleveland, Ohio (as by reference to the duly certified copy of letters testamentary here-
10 to annexed will more fully appear), believe said EDWARD F. McCool to have invented a new and useful Improvement in Grinding Mills, of which the following is a specification, the principle of the invention being
15 herein explained and the best mode in which it was contemplated applying that principle, so as to distinguish it from other inventions.

The present invention relates to coal pul-
20 verizing machinery, and more particularly, to a complete apparatus for pulverizing coal, ore or the like, in which means have been provided for positively feeding the material into the grinding chamber, thus pre-
25 venting packing or clogging of the inlet opening or pipe from the separator and making the feed positive. The entire apparatus has been illustrated as together with the power feed, certain other constructional
30 improvements, particularly as to the adjustment and arrangement of the grinding disks and the manner of mounting the feeding mechanism. To the accomplishment of the foregoing and related ends, said invention,
35 then, consists of the means hereinafter fully described and particularly pointed out in the claims.

The annexed drawing and the following description set forth in detail certain mecha-
40 nism embodying the invention, such dis-
closed means constituting, however, but one of various mechanical forms in which the principle of the invention may be used.

In said annexed drawing:—

45 Fig. 1 is a vertical sectional view through the machine; Fig. 2 is a top plan view with the operating mechanism shown in section; Fig. 3 is a front elevation; Fig. 4 is a rear elevation with the lower part in section;
50 Fig. 5 is a side elevational view; Fig. 6 is a sectional view on the line 6—6 of Fig. 3; and Fig. 7 is an end elevation of the feed screw supporting bearing.

In general the present apparatus com-
55 prises a crushing or grinding mill 1 directly

connected to a separator 2, the mill being provided with an outlet and classifier 3.

The mill comprises a suitable base 4 hav-
ing an elevated rear portion 5 on which is
55 mounted a suitable driving motor 6 having
a driving shaft 7. Mounted on the base is
the crusher housing 8 which is provided
with a power shaft 9 directly connected
through a suitable clutch coupling 10 to
the motor shaft 7, this shaft being carried
in large bearings 11 mounted in the hous-
ing. On this shaft is mounted a spur gear
12 and a worm gear 13, the worm gear
meshing with a worm wheel 14 on a cross
shaft 15, which also carries a bevel gear 16
70 meshing with a second bevel gear 17 carried on a longitudinal shaft 18 which is adjacent the top of the housing and adapted to furnish power for the separator shaft. The housing
is closed by a removable top member 29.

75 The main drive for the grinding appa-
ratus is through the gear 12 to a second
spur gear 20 keyed on a longitudinal sleeve
19 mounted in bearings 22, this sleeve be-
ing provided with an eccentric bore 21 in 80
which is mounted a shaft 23 which is ro-
tated through gears 24, 25, 26 and 27, gear
24 being keyed to the sleeve which is at this
point reduced to be concentric to the bore,
this driving gear 25 and thus gear 26, 85
mounted on a short shaft 28, the gear 26 be-
ing in mesh with gear 27 on the shaft 28,
the gears 25 and 26 being locked together
as shown in Fig. 1. Only a slight speed
change is made, the shaft being driven at a 90
slightly slower speed than the sleeve.

95 At the forward end of the machine there
is mounted a casing 30 of general cylindrical
shape which houses the grinding disks and
the fan mechanism, the fan 31 being mount-
ed in the outer portion of the casing and
consisting of fan blades 32 carried by a
spider 33 which is connected to the rotating
sleeve in any suitable manner so as to re-
volve therewith. Within the casing is 100
mounted a removable lining 215 to prevent
wear of the casing proper, the lining being
secured by bolts 216 or the like. Within the
fan blades is mounted a rotatable grinding
disk 35 which is provided at its rear side
with driving lugs 36 and a curved recess 37,
and this grinding disk is adapted to be
driven by means of the shaft 23 which is
provided with complementary driving lugs
38 adapted to interengage with those on the 105
110

disk and this shaft has a hemispherical end 39 which fits within the curved recess in the disk to support the same and also to allow pressure to be placed upon the disk and enable it to maintain a freedom to adjust itself to the plane of the stationary disk ring 40 which forms the other portion of the grinding chamber, which disk is removably attached to the door of the cylindrical fan chamber. These two disks are provided with substantially circular recesses 42 and 43 in which are inserted a series of grinding balls 44. The central portion of the grinding disk is concave and is provided with radial cutting or grinding ridges 45, and within the stationary disk ring 40 is a complementary concave stationary grinding member 46 likewise provided with grinding ridges 47, which member, with the central portion of the rotatable disk, forms the grinding chamber.

The closure for the fan and grinding chamber consists of an annular ring 50 which is bolted to the cylindrical casing and which is provided with a central aperture 51 adapted to receive a complementary formed portion 52 of the door which carries the two parts 40 and 46 of the stationary grinding disk. The annular ring is provided with grooves 48 in which is placed packing 49 or the like covered and contacted by the door to form a dust-proof joint. The center member 46 of the stationary grinding disk is provided with the central aperture 53 and this member also has an outwardly extending flange 54 which fits within a complementary formed flange 55 on the door proper, this flange extending rearwardly to form a housing and the door is also formed with an upwardly extending feed conduit 56 which is formed integrally with the housing, as best shown in Fig. 1. Within the housing and the extending flange of the stationary disk member is mounted a feed worm 57 which is tapered, that is, with the feed screw changing pitch and depth of thread slightly in order to have some crushing action. The inner shaft end 58 of this screw is carried in a three point bearing 59 formed on the stationary disk member, the three bearing portions being divided and leaving openings 60, as best shown in Fig. 7.

The feed screw housing is an integral part of the door mechanism or is rigidly secured thereto, and the entire door and housing consists of the door proper, the cylindrical portion 54 for the feed screw, the upwardly extending feed conduit 56, together with a continuation 62 of the end of the housing in which is mounted a horizontal shaft 63 carrying a bevel gear 64 in mesh with a bevel gear 65 in the end of the housing which is mounted on a short shaft 66 having a clutch member 67 con-

necting with the outer end of the feed screw shaft. The horizontal shaft is provided at its outer end with a worm gear or wheel 68 which meshes with a worm gear 220 pinned to a vertical shaft 69 carried in the housing which is provided with two bearing members 70 on each side of the worm screw, the shaft also having bearing in suitable bosses 71 on the main casing so that the door and complete housing may be swung about this shaft and worm screw, the lower member 70 bearing on the lower boss 71. At its upper end this vertical shaft is provided with a bevel gear 72 which meshes with a complementary gear 73 carried on a horizontal shaft 74 extending parallel to the driving sleeve of the machine. This shaft is mounted in a closed tube 75 connected to a supplementary casting 76 bolted to the main casing and opening into the latter and at the rear end the shaft is provided with a sprocket wheel 77 driven from a sprocket 78 mounted on the driving sleeve by a chain 79, an adjustable idler sprocket 221 being provided to compensate for wear or stretching of the chain.

The entire door mechanism, including the worm feed screw and driving mechanism therefore, and the housings and bearings which carry the driving shafts, are all mounted about the vertical shaft carrying the worm screw and may be swung about this shaft and worm screw as a pivot in order to allow the door to be swung open to obtain access to the grinding and fan chamber, the door being maintained in its closed position by the use of two or more flat strips 80 which are provided with slots 81 and secured to the annular ring of the casing by means of bolts 82 and nuts 83 so that when they are in the door engaging position, they may be locked fast over the door, as best shown in Fig. 3.

Mounted upon the casing for the grinding mechanism is a separator which consists of an outer chamber or housing 100 provided at the top with a funnel-shaped hopper 101 having an adjustable gate 85 actuated by a screw 86 through which the coal or ore is fed over a magnetic pulley 102 which is mounted on a horizontal shaft 103 carried in the housing, the larger particles being carried down by the pulley and being dropped into a chute 104 formed in the casing which communicates with the feed conduit to the feed screw, the lighter particles and dust being carried around by the air current entering through an upper adjustable damper into a second conduit 105 which is in communication with the fan chamber and being thence blown by means of the air up through the classifier from which it is passed to the furnace or the like. As shown in Fig. 3, a catch basin 87 is provided to receive the iron particles which are 130

scraped off the pulley by means of a scraper 88 which is mounted on the opposite side from the chute 104. The feed conduit is held tightly against the separator casing, packing grooves 89 and packing 90 being provided around the opening to form a dust-proof joint at this point.

The drive for the separating mechanism is best shown in Fig. 4 and consists of an eccentric 106 which is mounted on the shaft 18, and to this eccentric is connected a link 107 pivotally attached at one end to a double arm 108 which rocks about the pivotal point 109 of an adjustable slide 110 which is mounted on the arm. This arm is provided with a pin 111 on which are pivotally carried two links 112 and 113 which are connected at their upper ends to the extending outer ends 114 of clutch arms 115 which are adapted to engage with the pulley to drive the same. These clutch arms engage and turn the pulley in one direction only, and the clutches are preferably of the ball type so that downward movement of one arm will move the pulley while the pulley is moved by the upward movement of the other arm, thus letting the first arm move along the pulley to obtain a new grip as the pulley itself is being moved by the movement of the second arm.

The position of the slide 110 determines the drive of the pulley as when the pin or rocking point of the links coincides with the pivotal point of the slide, no movement will be given to the links at all and the arms will merely rock with the slide about the pivotal pin of the arms. The position of the slide will be determined by means of a bell crank 117 which is mounted on a shaft 118, the bell crank having its upper end in the form of a yoke 119 with two apertures 120 to receive the pivotal pins 121 of the slide. One arm 122 of the bell crank is pivotally connected to a link 123 which has a pivotal connection 45 at its upper end with an arm 124 carried on a shaft 125 mounted on the top of the separator casing, this shaft carrying the damper 126 controlling the air supply to the separator casing. Connected to the cross arms 122 and 127 of this bell crank are other links 128 and 129, which are connected to arms 130 which are adjustably connected to rock shaft 131 on which are mounted dampers which rock with the shafts, there being adjustable set screws 132 or the like to set the position of the arms relative to the dampers so that the control of the air supply to the fan is independent of the position of the slide to vary with different types of coal and yet the damper openings after once being set, vary with the slide position so that when the slide is in its neutral position, that is, with its pivotal point corresponding with the wrist pin of the arm, the dampers will 65 be closed or set at their normal position for

the type of coal being used and the pulley will not be operated. The shaft 118 to which the bell crank 117 is attached may be rotated to set the position of the slide and dampers, and this shaft, as shown, extends through the separator casing and is provided with a threaded portion 135 and a squared end 136 which may be engaged by a wrench to turn the shaft and bell crank, the shaft being locked in position by means of a lock nut 75 137 which bears against the face of the casing.

To effect the adjustment or the position of the grinding disks, the central shaft 23 mounted in the driving sleeve is adapted to have a longitudinal movement, this being accomplished by mounting the end of the shaft in a collar bushing 142, which carries the thrust bearing 142 which in turn bears against a cup 143 in the main housing, this cup being contacted at the rear by means of a plunger 144 which is engaged by a boss 145 on a lever 146, which is pivotally mounted on a suitable extension 147 of the machine casing, the member extending to the side of the casing and being attached at its outer end to a double rod 148 which extends along the machine where there is a link 149 pivotally mounted between the two rod ends, this link having pivotal connection in a yoked 95 end 150 of a bell crank 151 pivotally mounted about a bolt 152 carried by the casing. The angle arm 153 of the bell crank is a threaded rod held in place in the end of the crank 151 by a nut 154, this arm having a 100 weight 155 threaded thereon so as to be adjustable. The other end of the arm 153 is provided with a strap 156 which is slotted as at 157 to surround the double rod 148, the movement of the bell crank being limited 105 by the slot, the ends of which engage the double rod to limit movement in both directions.

At the other end of the machine the stationary disk ring is also adjustably mounted, 110 being carried on bolts 160 which pass through apertures in the door and which are supported in hollow bosses 162 on the feed screw housing being connected at their outer end by a cross member 163 which is secured in place by means of the nuts 164 on the bolt. This cross member is provided with a central hub 165 engaged by a similar portion 166 on a lever 167 pivotally mounted on the feed screw housing at 168, this lever 115 extending across the machine and being connected at its outer free end to a rod 169 which in turn is directly connected to one end 170 of a bell crank 171 similarly formed and weighted as the bell crank 151, being pivotally mounted on the machine case at 172 and having the threaded arm 173, weight 174 and strap 175 with the slot 176 to limit the movement of the bell crank.

The present coal pulverizer and handles 130

is a single complete unit, all parts being carefully enclosed and formed with the separator delivery mechanism and classifier attached thereto to form a unitary structure 5 adapted to receive separate pulverize and deliver coal or like substances.

The whole device is so constructed that parts may readily be changed or adjusted for wear and the automatic adjusting mechanism for the grinding disks is so arranged 10 that its limit of travel will indicate a complete wearing out of the grinding disks.

To aid in the assembly of the grinding members an opening 200 through stationary 15 disk and door is provided, the opening being placed near the top of the disk and being normally closed by a plug 201. The grinding balls may be inserted through this opening after the disks are set up and the 20 door closed.

The adjustable grinding disks with the weights maintain a constant pressure on the disks and the pulverized coal passes out between them the opening or spacing of the 25 disks varying with the internal pressure. If coal insufficiently pulverized passes out it is returned direct to the grinding chamber by force of gravity through a passage 202 leading back from the classifier which, as 30 shown, comprises an outlet pipe 203 which has an angle opening 204 into the classifying chamber, the pulverized coal coming out of the pipe 203 with the air stream and impinging against a movable plate 205 carried on an adjusting screw 206 rotatably 35 mounted through the upper wall of the classifier. At the other side of the chamber is the outlet conduit 207 from the classifier in which is slidably mounted a sleeve 40 208 having a spider 209 and a hub 210 which is tapped to receive an adjusting screw 211 extending through the bottom of the classifier and operable by a hand wheel 212 so that the course of air travel 45 may be varied as desired.

Other modes of applying the principle of my invention may be employed instead of the one explained, change being made as regards the mechanism herein disclosed, 50 provided the means stated by any of the following claims or the equivalent of such stated means be employed.

I therefore particularly point out and distinctly claim as my invention:

55 1. In a grinding mill, the combination of a power driven mill having fan and driving chamber at one end, a fan in said chamber, power means for driving said fan, a rotatable grinding disk in said chamber, 60 means for driving said disk, a closure for said chamber consisting of an annular ring secured to the open end of said chamber, and a door mounted in said annular ring, a stationary grinding disk attached to said 65 door and cooperating with said rotating

disk to act as the grinding mechanism, said stationary disk and said door being provided with a central aperture, a housing carried by said door and stationary disk and communicating with such central aperture, and a power driven feed screw mounted in said housing and adapted to receive the material to be ground and force the same through such central aperture to the grinding space between said two disks. 70

2. In a grinding mill, the combination of a power driven mill having fan and driving chamber at one end, a fan in said chamber, power means for driving said fan, a rotatable grinding disk in said chamber, means for driving said disk, a closure for said chamber consisting of an annular ring secured to the open end of said chamber, and a door mounted in said annular ring, a stationary grinding disk attached to said 80 door and cooperating with said rotating disk to act as the grinding mechanism, said stationary disk and said door being provided with a central aperture, a housing carried by said door and stationary disk and communicating with such central aperture, a power driven feed screw mounted in said housing and adapted to receive the material to be ground and force the same through such central aperture to the grinding space between said two disks, and a separator mounted on said mill to separate the material to be ground and provided with a chute adapted to deliver such material to 85 said feed screw. 90

3. In a grinding mill, the combination with a base provided with a power driven shaft, a fan and grinding chamber at one end of said mill, a fan and a rotatable grinding disk mounted in said chamber, means for driving said fan and disk from said power shaft, an annular ring mounted on said chamber, a housing pivotally attached to said base about a vertical axis and carrying a door adapted to fit within said annular ring to close said chamber, said door being provided with a central aperture and having a stationary grinding disk on its inner side, said disk also being provided with a central aperture, and material feeding means carried by said housing and door and comprising a second housing adjacent said door and disk apertures and a feed screw mounted in said housing and adapted to receive the material to be treated and feed 100 the same to said grinding disks. 115

4. In a grinding mill, the combination with a base provided with a power driven shaft, a fan and grinding chamber at one end of said mill, a fan and a rotatable grinding disk mounted in said chamber, means for driving said fan and disk from said power shaft, an annular ring mounted on said chamber, a housing pivotally attached to said base about a vertical axis and carrying 125 130

- a door adapted to fit within said annular ring to close said chamber, said door being provided with a central aperture and having a stationary grinding disk on its inner side, 5 said disk also being provided with a central aperture, and material feeding means carried by said housing and door and comprising a second housing adjacent said door and disk apertures and a feed screw mounted in said housing and adapted to receive the material to be treated and feed the same to said grinding disks, and driving means for said feed screw mounted in said first-named housing, and operatively connected to said 10 power driven shaft.
5. In a grinding mill, the combination with a base provided with a power driven shaft, a fan and grinding chamber at one end of said mill, a fan and a rotatable grinding disk mounted in said chamber, means for driving said fan and disk from said power shaft, an annular ring mounted on said chamber, a housing pivotally attached to said base about a vertical axis and carrying a door adapted to fit within said annular ring to close said chamber, said door being provided with a central aperture and having a stationary grinding disk on its inner side, said disk also being provided with a 15 central aperture, and material feeding means carried by said housing and door and comprising a second housing adjacent said door and disk apertures and a feed screw mounted in said housing and adapted to receive the material to be treated and feed the same to said grinding disks, driving means for said feed screw mounted in said first-named housing, and means operatively connecting said power-shaft with said feed screw driving 20 means.
6. In a grinding mill, the combination of a base, a fan and grinding chamber mounted at one end thereof, a closure for said chamber comprising an annular ring attached to said chamber, a fan rotatably mounted in said chamber, means for driving said fan comprising a power driven sleeve mounted in said base and connected to and supporting said fan, a rotatable grinding disk mounted in said chamber, means for driving said disk consisting of a rotatable driving shaft operatively driven from said sleeve, a longitudinally mounted rotatable shaft along one side of said base, a vertical shaft at the end of said base adjacent said grinding chamber, said vertical shaft being provided with gearing operatively connected to said longitudinal shaft, and being mounted in a suitable extension of said base, 25 said vertical shaft being provided with a worm screw, a housing pivotally mounted on said extension and having a worm wheel in engagement with said worm screw, said housing being pivotal about said vertical shaft and screw, a door having a central 30 aperture and carried by said housing and adapted to fit within said annular ring on said fan and grinding chamber, a stationary grinding disk mounted on said door and provided with a central aperture, a housing opening into such apertures through said door and stationary disk, a feed screw mounted in such latter housing and adapted to receive the material to be treated and feed the same to said grinding disks, and driving means carried in said first-named pivotally mounted housing and operatively connecting said worm wheel and said feed screw to drive the latter.
7. In feeding mechanism for grinding mills and the like, the combination with a mill having a base, a fan and grinding chamber, a fan and rotatable grinding disk therein of feeding and closure means for said chamber comprising an annular ring attached to said chamber, a housing pivotally mounted on said base about a vertical axis and provided with a secondary housing carrying a door adapted to be swung into place within said ring to close 35 said chamber, said door having a central aperture and being provided on its inner side with a stationary grinding disk having a central aperture, and a feed screw mounted in said secondary housing and adapted to receive and feed the material to be ground through said door and stationary disk.
8. In feeding mechanism for grinding mills and the like, the combination with a mill having a base, a fan and grinding chamber, a fan and rotatable grinding disk therein of feeding and closure means for said chamber comprising an annular ring attached to said chamber, a housing pivotally mounted on said base about a vertical axis and provided with a secondary housing carrying a door adapted to be swung into place within said ring to close 40 said chamber, said door having a central aperture and being provided on its inner side with a stationary grinding disk having a central aperture, and a feed screw mounted in said secondary housing and adapted to receive and feed the material to be ground through said door and stationary disk.
9. In feeding mechanism for grinding mills and the like, the combination with a mill having a base, a fan and grinding chamber, a fan and rotatable grinding disk therein of feeding and closure means for said chamber comprising an annular ring attached to said chamber, a housing pivotally mounted on said base about a vertical axis and provided with a secondary housing carrying a door adapted to be swung into place within said ring to close 45 said chamber, said door having a central aperture and being provided on its inner side with a stationary grinding disk having a central aperture, and a feed screw mounted in said secondary housing and adapted to receive and feed the material to be ground through said door and stationary disk, and driving means mounted in said housing and adapted to pivot therewith to drive said feed screw.
10. In feeding mechanism for grinding mills and the like, the combination with a mill having a base, a fan and grinding chamber, a fan and rotatable grinding disk therein of feeding and closure means for said chamber comprising an annular ring attached to said chamber, a housing pivotally mounted on said base about a vertical axis and provided with a secondary housing carrying a door adapted to be swung into place within said ring to close 50 said chamber, said door having a central aperture and being provided on its inner side with a stationary grinding disk having a central aperture, and a feed screw mounted in said secondary housing and adapted to receive and feed the material to be ground through said door and stationary disk, and driving means mounted in said housing and adapted to pivot therewith to drive said feed screw.
11. In feeding mechanism for grinding mills and the like, the combination with a mill having a base, a fan and grinding chamber, a fan and rotatable grinding disk therein of feeding and closure means for said chamber comprising an annular ring attached to said chamber, a housing pivotally mounted on said base about a vertical axis and provided with a secondary housing carrying a door adapted to be swung into place within said ring to close 55 said chamber, said door having a central aperture and being provided on its inner side with a stationary grinding disk having a central aperture, and a feed screw mounted in said secondary housing and adapted to receive and feed the material to be ground through said door and stationary disk, and driving means mounted in said housing and adapted to pivot therewith to drive said feed screw.
12. In feeding mechanism for grinding mills and the like, the combination with a mill having a base, a fan and grinding chamber, a fan and rotatable grinding disk therein of feeding and closure means for said chamber comprising an annular ring attached to said chamber, a housing pivotally mounted on said base about a vertical axis and provided with a secondary housing carrying a door adapted to be swung into place within said ring to close 60 said chamber, said door having a central aperture and being provided on its inner side with a stationary grinding disk having a central aperture, and a feed screw mounted in said secondary housing and adapted to receive and feed the material to be ground through said door and stationary disk, and driving means mounted in said housing and adapted to pivot therewith to drive said feed screw.
13. In feeding mechanism for grinding mills and the like, the combination with a mill having a base, a fan and grinding chamber, a fan and rotatable grinding disk therein of feeding and closure means for said chamber comprising an annular ring attached to said chamber, a housing pivotally mounted on said base about a vertical axis and provided with a secondary housing carrying a door adapted to be swung into place within said ring to close 65 said chamber, said door having a central aperture and being provided on its inner side with a stationary grinding disk having a central aperture, and a feed screw mounted in said secondary housing and adapted to receive and feed the material to be ground through said door and stationary disk, and driving means mounted in said housing and adapted to pivot therewith to drive said feed screw.

- said chamber, said door having a central aperture and being provided on its inner side with a stationary grinding disk having a central aperture, and a feed screw 5 mounted in said secondary housing and adapted to receive and feed the material to be ground through said door and stationary disk, and means for locking said door to said ring.
10. In feeding mechanism for grinding mills and the like, the combination with a mill having a base, a fan and grinding chamber, a fan and rotatable grinding disk therein of feeding and closure means for 15 said chamber comprising an annular ring attached to said chamber, a housing pivotally mounted on said base about a vertical axis and provided with a secondary housing carrying a door adapted to be 20 swung into place within said ring to close said chamber, said door having a central aperture and being provided on its inner side with a stationary grinding disk having a central aperture, and a feed screw 25 mounted in said secondary housing and adapted to receive and feed the material to be ground through said door and stationary disk, driving means mounted in 30 said housing and adapted to pivot therewith to drive said feed screw, and means for locking said door to said ring.
11. In feeding mechanism for grinding mills and the like, the combination with a mill having a base, a fan and grinding chamber, a fan and rotatable grinding disk 35 therein of feeding and closure means for said chamber comprising an annular ring attached to said chamber, a housing pivotally mounted on said base about a vertical axis and provided with a secondary 40 housing carrying a door adapted to be swung into place within said ring to close said chamber, said door having a central aperture and being provided on its inner side with a stationary grinding disk having a central aperture, and a feed screw 45 mounted in said secondary housing and adapted to receive and feed the material to be ground through said door and stationary disk, and means for locking said 50 door against said ring to form a dust-proof joint consisting of a packing groove in said ring, packing in said groove, an over-lapping flange on said door, and means for forcing said flange lightly against said 55 packing and securing said door in such closed position.

Signed by me, this 16th day of June, 1922.

ETHEL R. McCOOL,
Executrix of Edward F. McCool, deceased.
